RAILWAY SIGNAL CONTROL SYSTEM

William H. Claus, Downers Grove, Ill., assignor to
 Westinghouse Air Brake Company, a corpora-
 tion of Pennsylvania

Application February 11, 1948, Serial No. 7,553

10 Claims. (Cl. 246—3)

1

My invention relates to a railway signal control system, and particularly to a railway signal control system for signals for governing traffic movements in opposite directions over a stretch of single track railway.

In a railway signaling system of the well-known absolute permissive block type for a stretch of single track railway which is provided with passing sidings spaced along the single track, two pairs of head block signals, each comprising an entering and a leaving signal, are commonly employed for each passing siding for governing traffic movements in opposite directions, and are placed one pair adjacent each end of each passing siding. One or more pairs of intermediate signals for governing traffic movements in opposite directions are also commonly employed between consecutive passing sidings. Protection for opposing traffic movements between passing sidings is obtained by suitable arrangement of the intermediate signals, or by overlapping controls for the opposing leaving head block signals.

One feature of my invention is the provision of manually controllable means for at times providing overlapping control for the signals for one direction only of traffic movements, and for at other times providing overlapping control for the signals for the opposite direction only of traffic movements.

I shall describe one form of apparatus embodying my invention, and shall then point out the novel features thereof in claims.

The accompanying drawings, Figs. 1a and 1b, when placed side by side, with Fig. 1a on the left, constitute a diagrammatic view showing one form of apparatus embodying my invention, in which a stretch of single track railway is provided with passing sidings spaced along the single track railway, and in which two pairs of head block signals are employed for each passing siding and are placed one pair adjacent each end of each passing siding, and one pair of intermediate signals is employed between consecutive passing sidings for governing traffic movements in opposite directions; and in which manually controllable apparatus is provided for arranging overlap control for the signals for only one direction or the other at any given time.

Similar reference characters refer to similar parts in each of the drawings.

In each of the drawings, the contacts operated by the various relays or other devices are identified by numbers; each such number having a distinguishing prefix, from which it is separated by a dash, when the associated contact is shown

5 apart from the relay by which it is operated. The prefix for each of these contact numbers comprises the reference character for the respective relay by which the associated contact is operated. For example, contact ZSR-27, shown in Fig. 1b in a pick-up circuit for relay SHDR, is identified by the number 27 separated by a dash from the prefix ZSR which is the reference character for relay ZSR by which this contact is operated.

10 Referring further to the drawings, a portion of a single track railway is shown provided with passing sidings X and W. In order to simplify the drawings, each track, comprising two parallel series of track rails, is represented by a single line.

15 The portion of the single track railway shown in the drawings is divided by insulated joints 11 to form sections, each of which is designated by the reference character T preceded by a distinguishing numerical prefix. Each of the track sections is provided with a track circuit including a suitable source of current, such as a battery 12, connected across the rails adjacent one 20 end of the section, and a track relay, designated by the reference character TR with a distinguishing prefix, connected across the rails adjacent the opposite end of the section.

25 Adjacent each end of each of the passing sidings is a pair of head block signals for governing traffic movements in opposite directions. Signals 2S, 3S, 8S, and 9S, which govern traffic movements away from the passing sidings, are known as leaving signals, whereas signals 1S, 4S, 7S, and 10S, which govern traffic movements 30 toward the passing sidings, are known as entering signals. One pair of intermediate signals, 5S and 6S, governs traffic movements in opposite directions between the two consecutive passing

35 sidings. Signals 1S, 3S, 5S, 7S and 9S govern traffic movements toward the right, as shown in the drawings, which I shall assume is the eastbound direction, whereas signals 2S, 4S, 6S, 8S, and 10S govern traffic movements in the opposite 40 or westbound direction. The signals may be of any suitable design such, for example, as the color light type shown in the drawings, each of which comprises a green or clear lamp G, a yellow or caution lamp Y, and a red or stop lamp R.

45 Each of the signals is controlled by a polarized signal relay HDR having a numerical prefix which is the same as the numerical prefix in the reference character for its signal. Each of the signal relays HDR has a slow release neutral armature, and therefore its front contacts re-

main closed while its polar contacts are moving between their extreme positions. Each of the relays HDR is energized by current of normal or reverse polarity from a suitable source such, for example, as batteries 1Q and 2Q shown in the lower left-hand portion of Fig. 1a having a positive terminal B, a negative terminal N, and a common terminal C. The G, Y, and R lamps of each signal are lighted by circuits which are controlled by the associated signal relay, and which are similar to the circuits shown for signals 4S and 8S.

A polarized block repeater relay TP which has a slow release neutral armature is controlled by front contacts of relays 3TR, 5TR, and 8TR for the stretch of single track which includes sections 3T, 5T, and 8T between the pair of head block signals 3S and 4S adjacent the east end of siding X, and the pair of head block signals 1S and 8S adjacent the west end of siding W. The polarity of energization of relay TP is controlled by relay 4HDR.

Block stick relay TPS and a time element device TTE are controlled by a front contact of relay TP. Relay TPS is also controlled by time element device TTE, which may be of any suitable design such, for example, as the thermal type shown in Fig. 1b of the drawings.

A manually operable overlap control lever, designated by the reference character ZV, has a normal control position *n* and a reverse control position *r*. Contacts operated by lever ZV are shown as circles, in which are placed reference characters to show the positions of the lever in which the contacts are closed. Contact 64, for example, of lever ZV is closed when and only when lever ZV is in its reverse position *r*.

A polarized overlap control relay ZR is controlled by lever ZV and by relay TPS. Relay ZR is energized by current of normal polarity if lever ZV is in its normal or *n* position, and relay ZR is energized by current of reverse polarity if lever ZV is in its reverse or *r* position.

A neutral overlap indication relay ZP is energized in series with the winding of relay ZR.

A neutral overlap control relay ZRP is controlled by a normal contact of relay ZR.

Relay 2HDR may be controlled in any suitable manner by traffic conditions west of signal 2S. Relay 9HDR may be controlled in any suitable manner by traffic conditions east of signal 9S.

An energizing circuit for relay 4HDR includes front contacts of relays 1TR and 2TR, so that relay 4HDR will be deenergized when either of the relays 1TR and 2TR is deenergized. The polarity of energization of relay 4HDR is controlled by relay 2HDR.

Relay 6HDR is controlled by a circuit which includes front contacts of relays 4HDR, 3TR, and 5TR. Whenever either track section 3T or 5T is occupied by a train, causing relay 3TR or relay 5TR, respectively, to be deenergized, relay 6HDR will be deenergized. As shown in Fig. 1a, an auxiliary circuit path is closed around contact 19 of relay 4HDR through contact 20 of neutral overlap control relay ZRP, so that when contact 20 of relay ZRP is closed, relay 6HDR will not become deenergized when relay 4HDR becomes deenergized on account of relay 1TR or 2TR being deenergized. If, however, relay ZRP becomes deenergized, so that its contact 20 becomes opened, relay 6HDR will become deenergized when either relay 1TR or 2TR be-

comes deenergized, as well as when either relay 3TR or 5TR becomes deenergized.

Relay 8HDR is controlled by a normal control circuit which includes front contacts of relays 6HDR and 8TR. This circuit for relay 8HDR will therefore be opened if either relay 1TR or 2TR is deenergized while relay ZRP is deenergized, as well as when any one of the track relays 3TR, 5TR, and 8TR for the stretch of track between the pair of head block signals 3S and 4S and the pair of head block signals 1S and 8S is deenergized.

Relays 7HDR, 5HDR, and 3HDR are controlled by track relays similarly to relays 4HDR, 6HDR, and 8HDR, respectively, as just described. The polarity of energization of relay 7HDR is controlled by relay 9HDR.

Polarity control relays 4PCR and 7PCR are controlled by front and normal polar contacts of relays 4HDR and 7HDR, respectively. Relays 4PCR and 7PCR control the polarity of energization of relays 6HDR and 5HDR, respectively.

A direction stick relay 5SR associated with signal 5S is controlled in a well-known manner to become energized when an eastbound train enters section 5T while a front contact of relay 5HDR is closed, and to then remain energized by circuits controlled by back contacts of relays 5TR and 5HDR. A direction repeater relay 5SPR is controlled by a front contact of relay 5TR and by a back contact of relay 5SR. A second direction stick relay 6SR and a second direction repeater relay 6SPR for westbound traffic movements are controlled similarly to relays 5SR and 5SPR, respectively.

An overlap stick relay ZSR is controlled by a time element device ZTE, which may be of the thermal type, and by front contacts of relays 7HDR, 8HDR, and ZR, and also by a back contact of relay TPS. Contacts of relay ZSR are included in control circuits for relays 5HDR and 8HDR in order to delay the clearing of either signal 5S or 8S, respectively, for a measured period of time after the other of these signals has been controlled by lever ZV to indicate stop.

Overlap indication lamps *n*ZK and *r*ZK are controlled by overlap indication relay ZP and by lever ZV. Track occupancy indication lamps 1-2TK and 3-5-8TK are controlled by relay TP, and track occupancy indication lamp 7-9TK is controlled by relays 7TR and 9TR.

Having described, in general, the arrangement and control of the apparatus shown by the accompanying drawings, I shall now describe, in detail, its operation.

As shown in the drawings, all parts of the apparatus are in their normal condition, that is, each signal is displaying a green or clear indication; lever ZV is in its normal or *n* position; all track sections are unoccupied, and hence all track relays are energized; each signal relay HDR, block repeater relay TP, and overlap control relay ZR are energized by current of normal polarity; each of the relays 4PCR, 7PCR, ZRP, ZP, 5SPR, 6SPR, TPS, and ZSR is energized; each of the relays 5SR and 6SR is deenergized; indication lamp *n*ZK is lighted; and the other indication lamps are not lighted.

The circuit by which relay 4HDR is energized by current of normal polarity passes from terminal B of battery 1Q, through the front point of contact 13 of relay 2HDR, contacts 14 and 15 of relays 2TR and 1TR, respectively, and the winding of relay 4HDR to terminal C of batteries 1Q

and 2Q. Relay 7HDR is energized by a similar circuit.

Relay 4PCR is energized by a circuit passing from terminal B, through contacts 16 and 17 of relay 4HDR, and the winding of relay 4PCR to terminal C. Relay 7PCR is energized by a circuit which is similar to that just traced for relay 4PCR.

The circuit by which relay 6HDR is energized by current of normal polarity passes from terminal B, through the front point of contact 18 of relay 4PCR, contact 19 of relay 4HDR in multiple with contact 20 of relay ZRP, contact 21 of relay 3TR, contact 22 of relay 5TR, and the winding of relay 6HDR to terminal C.

A pick-up circuit is closed for energizing relay 8HDR by current of normal polarity, this circuit passing from terminal B, through contact 23 of relay 6HDR, back point of contact 24 of relay 6SR, contact 25 of relay 5SPR, contact 26 of relay 8TR, contact ZSR-27, and the winding of relay 8HDR to terminal C. A stick circuit is also closed for relay 8HDR, which is the same as the pick-up circuit just traced except that it includes contact 28 of relay 8HDR instead of contact ZSR-21.

Relay 5HDR is energized by current of normal polarity passing from terminal B, through the front point of contact 29 of relay 7PCR, contact 30 of relay 7HDR, contact 33 of relay 8TR, contact 34 of relay 5TR, and the winding of relay 5HDR to terminal C.

Relay 3HDR is energized by current of normal polarity passing from terminal B, through contact 35 of relay 5HDR, back point of contact 36 of relay 5SR, contact 37 of relay 6SPR, contact 38 of relay 3TR, and the winding of relay 3HDR to terminal C.

The green lamp G of signal 4S is lighted by current passing from terminal EB of a suitable source of lighting current, through front point of contact 39 of relay 4HDR, contact 40 of relay 4HDR closed in the normal or left-hand position, and lamp G to terminal EN of the same source of lighting current. Green lamp G of each of the other signals is lighted by circuits which are similar to that just traced for signal 4S.

Direction repeater relay 5SPR is energized by a circuit passing from terminal B, through contact 41 of relay 5SR, contact 42 of relay 5TR, and the winding of relay 5SPR to terminal C. Relay 6SPR is energized by a similar circuit.

Relay TP is energized by current of normal polarity passing from terminal B, through the front point of contact 44 of relay 4HDR, contact 45 of relay 3TR, contact 46 of relay 5TR, contact 47 of relay 8TR, and the winding of relay TP to terminal C.

Relay TPS is energized by a stick circuit passing from terminal B, through contact 48 of relay TP, front point of contact 49 of relay TPS, and the winding of relay TPS to terminal C.

Overlap control relay ZR and overlap indication relay ZP are energized in series with each other by current of normal polarity passing from terminal B, through contact 51 of lever ZV, winding of relay ZP, contact 52 of relay TPS, and the winding of relay ZR to terminal C.

Relay ZRP is energized by a circuit passing from terminal B, through contact 54 of relay ZR, and the winding of relay ZRP to terminal C.

A stick circuit for relay ZSR is closed, passing from terminal B, through contact 55 of relay 8HDR, contact 56 of relay 7HDR, front point of contact 59 of relay ZSR, and the winding of relay ZSR to terminal C. A second stick circuit is also

closed for energizing relay ZSR, this circuit being the same as the first stick circuit just traced except that it includes contact 57 of relay ZR instead of contacts 55 and 56 of relays 8HDR and 7HDR, respectively.

Lamp nZK is lighted by a circuit passing from terminal EB, through contact 61 of relay ZP, contact 62 of lever ZV, and lamp nZK to terminal EN.

I shall assume that, with apparatus embodying my invention as shown in the accompanying drawings thus in the normal condition, an east-bound train approaches signal 1S and deenergizes relay 2HDR, causing green lamp G of signal 2S to be extinguished, and causing red lamp R of this signal to be lighted by a circuit which is similar to the circuit traced for lamp R of signal 4S.

With relay 2HDR deenergized, relay 4HDR will now be energized by current of reverse polarity passing from terminal C, through the winding of relay 4HDR, contact 15 of relay 1TR, contact 14 of relay 2TR, and the back point of contact 13 of relay 2HDR to terminal N of battery 2Q. With relay 4HDR energized by current of reverse polarity, green lamp G of signal 4S will be extinguished, and lamp Y of this signal will become lighted by a circuit passing from terminal EB, through the front point of contact 39 of relay 4HDR, contact 40 of relay 4HDR in the reverse position, and lamp Y of signal 4S to terminal EN.

When relay 4HDR becomes energized by current of reverse polarity, its contact 17 opens the circuit previously traced for relay 4PCR, causing relay 4PCR to become deenergized.

With relay 4PCR deenergized, relay 6HDR is energized by current of reverse polarity passing from terminal C through the winding of relay 6HDR, contact 22 of relay 5TR, contact 21 of relay 3TR, contact 19 of relay 4HDR in multiple with contact 20 of relay ZRP, and the back point of contact 18 of relay 4PCR to terminal N. With relay 6HDR thus energized by current of reverse polarity, green lamp G of signal 6S will be extinguished, and yellow lamp Y of signal 6S will be lighted by a circuit which is similar to the circuit previously traced for signal 4S.

When the eastbound train enters section 2T, contact 14 of relay 2TR opens the circuit previously traced for relay 4HDR, causing relay 4HDR to become deenergized. With relay 4HDR deenergized, yellow lamp Y of signal 4S becomes extinguished, and red lamp R of this signal becomes lighted by a circuit passing from terminal EB, through the back point of contact 39 of relay 4HDR, and lamp R of signal 4S to terminal EN.

Contact 19 of relay 4HDR is now open in the circuits traced for relay 6HDR which, however, remains energized by current of reverse polarity because contact 20 of relay ZRP is still closed.

With relay 4HDR deenergized, relay TP is energized by current of reverse polarity passing from terminal C through the winding of relay TP, contacts 41, 46 and 45 of relays 8TR, 5TR, and 3TR, respectively, and the back point of contact 44 of relay 4HDR, to terminal N. Relay TP, upon becoming energized by current of reverse polarity, completes a circuit for lighting lamp 1-2TK, this circuit passing from terminal EB, through the front point of contact 65 of relay TP, contact 66 of relay TP, and lamp 1-2TK to terminal EN.

When the train leaves section 2T, relay 2HDR again becomes energized, causing lamp R of sig-

nal 2S to become extinguished and lamp G of this signal to become lighted by a circuit which is similar to the circuit traced for signal 4S. Relay 4HDR, however, now remains deenergized because its circuit is open at contact 15 of relay 1TR.

When the train enters section 3T, contact 38 of relay 3TR opens the circuit traced for relay 3HDR, causing relay 3HDR to become deenergized. Contact 21 of relay 3TR also opens the circuit for relay 6HDR, causing relay 6HDR to also become deenergized. With relay 3HDR deenergized, green lamp G of signal 3S becomes extinguished, and red lamp R of this signal becomes lighted. With relay 6HDR deenergized, yellow lamp Y of signal 6S becomes extinguished, and red lamp R of this signal becomes lighted.

With relay 6HDR deenergized, the circuit previously traced for relay 8HDR becomes opened at contact 23 of relay 6HDR, causing relay 8HDR to become deenergized. With relay 8HDR deenergized, green lamp G of signal 8S becomes extinguished, and red lamp R of this signal becomes lighted by a circuit which is similar to the circuit previously traced for signal 4S.

With relay 3TR deenergized, relay TP is now deenergized on account of contact 45 of relay 3TR being open. With relay TP deenergized, indication lamp 1-2TK becomes extinguished, and lamp 3-5-8TK becomes lighted by a circuit passing from terminal EB, through the back point of contact 65 of relay TP, and lamp 3-5-8TK to terminal EN.

Relay TP, upon becoming deenergized, permits contact 48 to open, thereby deenergizing relay TPS.

Relay ZR, therefore, now becomes deenergized because contact 52 of relay TPS becomes opened. Relay ZP, which is in series with relay ZR is also deenergized, and therefore its contact 61 opens the circuit previously traced for lamp nZK, causing this lamp to be extinguished.

Relay TPS, upon becoming deenergized, completes a third stick circuit for relay ZSR, this circuit passing from terminal B, through contact TPS-58, front point of contact 59 of relay ZSR, and the winding of relay ZSR to terminal C. Relay ZSR, therefore, remains energized because contact TPS-58 becomes closed before contact 57 of relay ZR opens, and also before contact 55 of relay 8HDR opens the first stick circuit traced for relay ZSR.

When the train leaves section 1T, relay 4HDR again becomes energized by current of normal polarity, causing lamp R of signal 4S to become extinguished, and lamp G of this signal to again be lighted. With relay 4HDR again energized by current of normal polarity, relay 4PCR again becomes energized by its circuit previously traced.

When the train enters section 5T, contact 34 of relay 5TR opens the circuit previously traced for relay 5HDR, causing this relay to become deenergized. With relay 5HDR deenergized green lamp G of signal 5S becomes extinguished, and red lamp R of this signal becomes lighted.

When relay 5TR becomes deenergized, its contacts 42 and 43 open the circuits for relays 5SPR and 6SPR, respectively, causing these relays to be deenergized.

Because the neutral armature of relay 5HDR is slow in releasing, its contact 71 remains closed for a brief period of time at its front point after relay 5HDR becomes deenergized. Relay 5SR, therefore, becomes energized by its pick-up circuit passing from terminal B, through contact 75

10 of relay 5TR, front point of contact 71 of relay 5HDR, and the winding of relay 5SR to terminal C. Relay 5SR, upon becoming energized, completes a first stick circuit passing from terminal B, through contact 70 of relay 5TR, contact 72 of relay 5SR, and the winding of relay 5SR to terminal C. When relay 5HDR releases its neutral armature, a second stick circuit becomes closed which is the same as the first stick circuit already traced for relay 5SR except that it includes the back point of contact 71 of relay 5HDR instead of contact 70 of relay 5TR.

When the train enters section 8T, causing relay 8TR to become deenergized, contacts 26, 33 and 47 of this relay become opened in the circuits for relays 8HDR, 5HDR, and TP which are, however, already deenergized because relay 5TR is deenergized.

When the train leaves section 5T, relay 6SPR again becomes energized by its circuit previously described. Relay 3HDR, therefore, now becomes energized by current of reverse polarity passing from terminal C, through the winding of relay 3HDR, contact 38 of relay 3TR, contact 37 of 20 relay 6SPR, and the front point of contact 36 of relay 5SR to terminal C. With relay 3HDR energized by current of reverse polarity, lamp R of signal 3S becomes extinguished and lamp Y of this signal becomes lighted. When the train leaves section 5T, relay 6HDR again becomes energized by current of normal polarity, causing lamp R of this signal to be extinguished and its lamp G to be lighted.

When the train enters section 7T, deenergizing relay 7TR, relay 7HDR becomes deenergized, causing lamp G of signal 7S to be extinguished, and lamp R of this signal to be lighted. With relay 7TR deenergized, indication lamp 7-9TK becomes lighted by a circuit passing from terminal EB, through contact 67 of relay 7TR, and lamp 7-9TK to terminal EN.

When the train leaves section 8T, relay TP again becomes energized by current of normal polarity in its circuit previously traced. With 45 relay TP energized, a circuit is completed for energizing time element device TTE, this circuit passing from terminal B, through contact 48 of relay TP, back point of contact 49 of relay TPS, and the control element of time element device 50 TTE to terminal C. Upon the lapse of a measured period of time, contact 50 of time element device TTE completes a pick-up circuit for relay TPS, this circuit passing from terminal B, through contact 48 of relay TP, contact 50 of time element device TTE, and the winding of relay TPS to terminal C. Relay TPS, upon becoming energized, completes its stick circuit previously traced.

Since relay TPS does not become energized until the lapse of a measured period of time after relay TP becomes energized, relay ZSR remains energized by its third stick circuit previously traced long enough that relay 8HDR becomes energized by its pick-up circuit previously traced.

When relay TPS becomes energized, relays ZR and ZP again become energized by their circuit previously traced. With relay ZP again energized, lamp nZK again becomes lighted by its circuit previously traced.

When the train enters section 9T, relay 9HDR becomes deenergized, causing lamp G of signal 9S to be extinguished, and lamp R of this signal to be lighted.

While the train is moving through sections

IT and 9T, relay 5HDR remains deenergized because contact 30 of relay 7HDR is open and contact 31 of relay ZR is open. Signal 5S, therefore, continues to indicate stop.

When the train leaves section 9T, relay 7HDR becomes energized by current of reverse polarity, causing lamp Y of signal 7S to be lighted. With relay 7HDR energized by current of reverse polarity, so that relay 1PCR is deenergized, a circuit is completed for energizing relay 5HDR by current of reverse polarity, this circuit passing from terminal C, through the winding of relay 5HDR, contact 34 of relay 5TR, contact 33 of relay 8TR, contact 30 of relay 7HDR, and the back point of contact 29 of relay 1PCR to terminal N. Yellow lamp Y of signal 5S, therefore, now becomes lighted. With relays 5TR and 5HDR now both energized, relay 5SR becomes deenergized, and hence the circuit is again completed for energizing relay 3HDR by current of normal polarity. Green lamp G of signal 3S, therefore, now becomes lighted.

I shall next assume that all parts of the apparatus are again in the normal condition, and that an eastbound train passes signal 1S and is approaching signal 3S. I shall also assume that a westbound train deenergizes relay 9TR, so that signals 9S and 7S are indicating stop. With relay 7HDR deenergized, contact 30 of this relay is open in the circuits previously traced for relay 5HDR, so that relay 5HDR becomes deenergized, causing relay 3HDR in turn to also be deenergized. Signals 5S and 3S also will therefore indicate stop.

I shall assume further that the two trains are to pass each other with the eastbound train moving onto passing siding W, while the westbound train remains on section 7T of the main track.

A leverman or dispatcher therefore moves lever ZV to its *r* position for energizing relay ZR by current of reverse polarity for thereby rendering ineffective the overlap control of relay 5HDR through contact 30 of relay 7HDR. The circuit by which relay ZR becomes energized by current of reverse polarity passes from terminal C, through the winding of relay ZR, contact 52 of relay TPS, winding of relay ZP, and contact 53 of lever ZV to terminal N. Lever ZV, upon being moved to its *r* position, extinguishes lamp nZK, and then completes a circuit passing from terminal EB, through contact 63 of relay ZP, contact 64 of lever ZV, and lamp rZK to terminal EN, causing lamp rZK to now become lighted.

With relay ZR energized by current of reverse polarity, its contact 54 opens the circuit for relay ZRP, causing contact 20 of relay ZRP to become opened. With the eastbound train on section 1T, relay 4HDR is also deenergized, and therefore contact 19 of relay 4HDR, as well as contact 20 of relay ZRP, is open, causing relay 6HDR to become deenergized. With relay 6HDR deenergized, its contact 23 opens the circuit for relay 8HDR, causing relay 8HDR to also be deenergized. With relays 6HDR and 8HDR now both deenergized, signals 6S and 8S are both displaying the red or stop indication.

The neutral armature of relay ZR is not of the slow releasing type, and therefore when lever ZV is moved from its *n* to its *r* position, contact 57 of relay ZR becomes opened, so that relay ZSR becomes deenergized because its first pick-up circuit is already open at contact 56 of relay 7HDR, and its third pick-up circuit is open at contact TPS-58. Contact ZSR-32 is therefore

opened in the auxiliary circuit path around contact 30 of relay 7HDR.

After contact 31 of relay ZR becomes closed, contact 57 of relay ZR again becomes closed, thereby completing a circuit for energizing time element device ZTE, this circuit passing from terminal B, through contact 51 of relay ZR, back point of contact 59 of relay ZSR, and the control element of device ZTE to terminal C. Upon the lapse of a measured period of time, a pick-up circuit becomes closed for relay ZSR, passing from terminal B, through contact 57 of relay ZR, contact 60 of time element device ZTE, and the winding of relay ZSR to terminal C. Relay ZSR, upon becoming energized, completes a circuit for energizing relay 5HDR by current of reverse polarity, which is the same as the circuit previously traced for energizing this relay by current of reverse polarity except that it includes contact ZSR-32 and contact 31 of relay ZR instead of contact 30 of relay 7HDR. With relay 5HDR energized by current of reverse polarity, yellow lamp Y of signal 5S will now be lighted, and relay 3HDR will become energized by current of normal polarity, causing lamp G of signal 3S to be lighted.

From the foregoing description, it follows that because of the timed element control of relay ZSR when lever ZV is moved from its *n* to its *r* position for causing signals 6S and 8S to display the stop indication, signal 3S will not at once be controlled to display the green indication, but will continue to indicate stop for a measured period of time. The eastbound train will then pass signal 3S displaying a green indication and signal 5S displaying the yellow indication.

When the eastbound train moves onto passing siding W and leaves section 8T, relay 5HDR will again become energized by current of reverse polarity in the circuit through contact 31 of relay ZR, and relay 3HDR will again become energized by current of normal polarity. Signal 5S, therefore, will again display the yellow indication, and signal 3S will display the green indication.

I shall now assume further that a second eastbound train has entered section 2T and is approaching signal 1S. Relay 4HDR is, therefore, deenergized. Contact 19 of relay 4HDR will therefore be open, as well as contact 20 of relay ZRP, so that relay 6HDR will remain deenergized, and therefore relay 8HDR will also remain deenergized, so that signals 6S and 8S will continue to indicate stop after the first eastbound train leaves section 8T.

I shall assume, however, that the dispatcher decides to have the westbound train and the second eastbound train pass each other at passing siding X. He will, therefore, return lever ZV to its *n* position after the first eastbound train has left section 8T. Relay ZR will, therefore, again become energized by current of normal polarity and will open its contact 31, thereby deenergizing relay 5HDR which in turn deenergizes relay 3HDR, causing signals 5S and 3S to again display the stop indication. With relay ZR again energized by current of normal polarity, relay ZRP is again energized by its circuit previously traced, so that relay 6HDR is again energized by current of reverse polarity, causing signal 6S to display the yellow indication.

Movement of lever ZV from its *r* to its *n* position causes contact 57 of relay ZR to open the stick circuit for relay ZSR, so that relay ZSR

becomes deenergized, and therefore relay 8HDR cannot become energized by its pick-up circuit until relay ZSR again becomes energized after the lapse of a measured period of time for energizing time element device ZTE after the completion of the movement of lever ZV to its *n* position.

It follows that, after the dispatcher causes signals 3S and 5S to indicate stop by the movement of lever ZV from its *r* to its *n* position, a measured period of time must elapse before signal 8S will clear. One purpose of relay ZSR and its time element device ZTE is to accomplish this result.

If, under the conditions just described, the dispatcher, instead of waiting until the first eastbound train leaves section 8T, returns lever ZV to its *n* position while the first eastbound train is on section 8T, relay ZSR will remain energized by its stick circuit including contact TPS-58 as long as relay TPS remains deenergized. During the period of time required for time element device TTE to close its contact 50 for energizing relay TPS after the eastbound train then leaves section 8T, relay 5HDR would become energized by current of reverse polarity by its circuit including contact ZSR-32 and contact 31 of relay ZR. While relay TPS is deenergized, its contact 52 is open, and therefore relay ZR cannot become energized by current of normal polarity although lever ZV has been returned to its *n* position. Relay 5HDR, upon becoming energized, opens the back point of its contact 71, thereby deenergizing relay 5SR.

When relay TPS becomes energized, its contact TPS-58 opens the stick circuit for relay ZSR, and its contact 52 closes the normal energizing circuit for relay ZR. Contact 51 of relay ZR does not then become closed until after the polar contacts of relay ZR have been returned to the normal position, so that relay ZSR becomes deenergized between the time when contact TPS-58 opens and the time when contact 51 of relay ZR closes.

With relay ZR again energized by current of normal polarity, relay ZRP will become energized, so that relay 6HDR will again become energized by current of reverse polarity, causing signal 6S to display the yellow indication. Relay 8HDR, however, will not again become energized by current of normal polarity until relay ZSR becomes energized after the lapse of a measured period of time, as previously described.

It follows that one purpose of relay TPS and its time element device TTE is to introduce a time interval to permit relay 5HDR or relay 6HDR to become energized for a brief period of time for restoring relay 5SR or relay 6SR, respectively, to its deenergized condition when lever ZV is moved from one of its control positions to the other while relay TP is deenergized by a train on the stretch of track between the pair of signals 3S and 4S and the pair of signals 7S and 8S.

I have described the operation of the apparatus for a few typical traffic movements. It is believed that, in view of this description, the operation of the apparatus for any other possible traffic movement can be readily understood by reference to the drawings.

Although I have herein shown and described only one form of apparatus embodying my invention, it is understood that various changes and modifications may be made thereto within the scope of the appended claims without de-

parting from the spirit and scope of my invention.

Having thus described my invention, what I claim is:

- 5 1. In a control system for signals for a stretch of single track railway including a first pair of automatic signals adjacent a given end of said stretch and a second pair of automatic signals adjacent the opposite end of said stretch, a given signal of each of said pairs arranged for governing traffic movements onto said stretch and the other signal of each of said pairs arranged for governing traffic movements off of said stretch, and including a pair of automatic intermediate signals between said first and second pairs of signals for governing traffic movements in opposite directions, the combination comprising, manually controllable means for at times extending the automatic control of one of said given signals and of one of said intermediate signals beyond the end of said stretch in a given direction to control said one given signal and said one intermediate signal to indicate stop if a track section is occupied beyond the end of said stretch in said given direction, and other manually controllable means for at other times extending the automatic control of the other given signal and of the other of said intermediate signals beyond the end of said stretch in the opposite direction to control said other given signal and said other intermediate signal to indicate stop if a track section is occupied beyond the end of said stretch in said opposite direction only while said first manually controllable means is ineffective for extending the automatic control of said one given signal and of said one intermediate signal.
- 10 2. In a control system for signals for a stretch of single track railway including a first pair of signals for governing traffic movements in opposite directions adjacent a given end of said stretch and a second pair of signals for governing traffic movements in opposite directions adjacent the opposite end of said stretch, and including a pair of intermediate signals for governing traffic movements in opposite directions between said first and second pairs of signals, the combination comprising, manually controllable means for at times arranging for a given signal of said first pair and a signal of said intermediate pair for a given direction of traffic movements to be controlled to indicate stop by traffic conditions in said given direction beyond said second pair of signals as well as by traffic conditions on said stretch while a given signal of said second pair and the other signal of said intermediate pair for the opposite direction of traffic movements are controlled to indicate stop by traffic conditions on said stretch only, and said manually controllable means at other times arranging for said given signal of said second pair and said other signal of said intermediate pair to be controlled to indicate stop by traffic conditions in said opposite direction beyond said first pair of signals as well as by traffic conditions on said stretch while said given signal of said first pair and said first signal of said intermediate pair are controlled to indicate stop by traffic conditions on said stretch only.
- 15 3. In a control system for signals for a stretch of single track railway including a first pair of signals for governing traffic movements in opposite directions adjacent a given end of said stretch and a second pair of signals for governing traffic movements in opposite directions ad-

jacent the opposite end of said stretch, the combination comprising, manually controllable means for at times arranging for a given signal of said first pair to be controlled to indicate stop if a track section beyond the opposite end of said stretch is occupied as well as if said stretch of track is occupied by a train which is approaching said given signal of said first pair from said opposite end of said stretch and for arranging for a given signal of said second pair to indicate stop only if said stretch of track is occupied by a train which is approaching said given signal of said second pair from said given end of said stretch and only if said manually controllable means is in condition for controlling said given signal of said first pair to indicate stop if said track section beyond said opposite end of said stretch is occupied, and said manually controllable means at other times arranging for said given signal of said second pair to be controlled to indicate stop if a track section beyond said first pair in said opposite direction is occupied as well as if said stretch is occupied and for at said other times also arranging for said given signal of said first pair to indicate stop only if said stretch is occupied.

4. In a control system for signals for a stretch of single track railway including a first pair of signals for governing traffic movements in opposite directions adjacent a given end of said stretch and a second pair of signals for governing traffic movements in opposite directions adjacent the opposite end of said stretch, the combination comprising, a control circuit for a given signal of said first pair controlled by traffic conditions on said stretch and controlled by a contact which is closed if a track section adjacent said opposite end of said stretch is unoccupied but becoming opened if said track section becomes occupied, a control circuit for a given signal of said second pair controlled by traffic conditions on said stretch and controlled by a second contact which is closed if a second track section adjacent said given end of said stretch is unoccupied but becoming opened if said second track section becomes occupied, and manually controllable means for at times closing a circuit path around said first contact and for at other times closing a circuit path around said second contact.

5. In a control system for signals for a stretch of single track railway including a first pair of signals for governing traffic movements in opposite directions adjacent a given end of said stretch and a second pair of signals for governing traffic movements in opposite directions adjacent the opposite end of said stretch, the combination comprising, a control circuit for a given signal of said first pair controlled by traffic conditions on said stretch and controlled by a contact which is closed if a track section adjacent said opposite end of said stretch is unoccupied but becoming opened if said track section becomes occupied, a control circuit for a given signal of said second pair controlled by traffic conditions on said stretch and controlled by a second contact which is closed if a second track section adjacent said given end of said stretch is unoccupied but becoming opened if said second track section becomes occupied, a manually controllable device having a normal and a reverse position, means controlled by said device in its normal position for closing a circuit path around said first contact, and means controlled by said device in its reverse position for closing a circuit path around said second contact.

6. In a control system for signals for a stretch of single track railway including a first pair of signals for governing traffic movements in opposite directions adjacent a given end of said stretch and a second pair of signals for governing traffic movements in opposite directions adjacent the opposite end of said stretch, the combination comprising, a control circuit for a given signal of said first pair controlled by traffic conditions on said stretch and controlled by a contact which is closed if a track section adjacent said opposite end of said stretch is unoccupied but becoming opened if said track section becomes occupied, a control circuit for a given signal of said second pair controlled by traffic conditions on said stretch and controlled by a second contact which is closed if a second track section adjacent said given end of said stretch is unoccupied but becoming opened if said second track section becomes occupied, a stick relay, a pick-up and a stick circuit for said stick relay each of which is closed only if said stretch of track is unoccupied and said pick-up circuit also controlled by a time element device, an energizing circuit for said time element device controlled by a back contact of said stick relay and closed only if said stretch of track is unoccupied, and manually controllable means controlled also by a front contact of said stick relay for at times closing a circuit path around said first contact and for at other times closing a circuit path around said second contact.

7. In a control system for signals for a stretch of single track railway including a first pair of signals for governing traffic movements in opposite directions adjacent a given end of said stretch and a second pair of signals for governing traffic movements in opposite directions adjacent the opposite end of said stretch, the combination comprising, a control circuit for a given signal of said first pair controlled by traffic conditions on said stretch and controlled by a first contact which is closed if a track section adjacent said opposite end of said stretch is unoccupied but becoming opened if said track section becomes occupied, a control circuit for a given signal of said second pair controlled by traffic conditions on said stretch and controlled by a second contact which is closed if a second track section adjacent said given end of said stretch is unoccupied but becoming opened if said second track section becomes occupied, a stick relay, a time element device, a manually controllable device having a normal and a reverse control position, a pick-up circuit for said stick relay controlled by a front contact of said time element device and closed only if both signals of said first pair are controlled to display an indication other than stop, a second pick-up circuit for said stick relay controlled by a front contact of said time element device and including a contact which is normally closed if said stretch of track is unoccupied but which becomes opened for a brief period of time when said manually controllable device is moved from either of its control positions to the other, a first and a second stick circuit for said stick relay which are the same as said first and second pick-up circuits respectively except that said stick circuits include a front contact of said stick relay instead of being controlled by a front contact of said time element device, means including a back contact of said stick relay for effecting energization of said time element device, means controlled by said manually controllable device in its normal and reverse positions for closing a cir-

cuit path around said first and second contacts respectively in said signal control circuits, and means controlled by said stick relay to prevent clearing either of said given signals until a measured period of time has elapsed after the other given signal has been controlled to display the stop indication.

8. In a control system for signals for a stretch of single track railway including a first pair of signals for governing traffic movements in opposite directions adjacent a given end of said stretch and a second pair of signals for governing traffic movements in opposite directions adjacent the opposite end of said stretch, in which a given signal of each of said pairs is controlled to indicate stop if said stretch of track is occupied, the combination comprising, manually controllable means for at times also controlling one of said given signals to indicate stop if a track section beyond said stretch in the direction of traffic movements governed by said one given signal is occupied, and other manually controllable means for at other times also controlling the other of said given signals to indicate stop if a track section beyond said stretch in the direction of traffic movements governed by said other given signal is occupied only while said first manually controllable means is ineffective for controlling said one of said given signals to indicate stop if a track section beyond said stretch is occupied.

9. In a control system for signals for a stretch of single track railway including a first pair of signals for governing traffic movements in opposite directions adjacent a given end of said stretch and a second pair of signals for governing traffic movements in opposite directions adjacent the opposite end of said stretch, in which a given signal of each of said pairs is controlled to indicate stop if said stretch of track is occupied, the combination comprising, manually controllable means for at times also controlling one of said given signals to indicate stop if a track section beyond said stretch in the direction of traffic movements governed by said one given signal is occupied and for at other times also controlling

5 the other of said given signals to indicate stop if a track section beyond said stretch in the direction of traffic movements governed by said other given signal is occupied, and time element means controlled by said manually controllable means to delay clearing either of said given signals for a measured period of time if the other of said given signals is controlled by said manually controllable means to indicate stop.

10. In a control system for signals for a stretch of single track railway including a first pair of signals for governing traffic movements in opposite directions adjacent a given end of said stretch and a second pair of signals for governing traffic movements in opposite directions adjacent the opposite end of said stretch, in which a given signal of each of said pairs is controlled to indicate stop if said stretch of track is occupied, the combination comprising, a manually controllable device having a normal control position for at times also controlling one of said given signals to indicate stop if a track section beyond said stretch in the direction of traffic movements governed by said one given signal is occupied and having a reverse control position for at other times also controlling the other of said given signals to indicate stop if a track section beyond said stretch in the direction of traffic movements governed by said other given signal is occupied, and means controlled by said manually controllable device upon being moved from either of its control positions to the other for delaying the clearing of either of said given signals for a measured period of time if the other of said given signals is controlled by said manually controllable device to indicate stop.
